ELECTRIC CLOCK

Arthur F. Poole, Ithaca, N. Y.; Maryline B. Poole, administratrix of said Arthur F. Poole, deceased, assignor to Maryline B. Poole, Ithaca, N. Y.

Application August 22, 1931, Serial No. 558,773

6 Claims. (Cl. 58—26)

My invention is an electric clock of the type run from a regulated A. C. current. By regulated current, I mean a current whose frequency is regulated at the power house so that the average 5 cycles per second of the current is exactly some predetermined number, usually 60.

One of the objects of my invention is a clock of this type which will bridge over a period of no current and so keep up the motion of the clock 10 hands during a short period of interruption to the current supply. Another object of my invention is the provision of a recoil escapement in a clock of this type to the end that the clock will start itself as soon as power is supplied to it, and 15 not have to be started by outside means as is the case of clocks with a detached escapement (for example, a lever escapement) heretofore used.

A further object of my invention is the elimination of the synchronous motor used in clocks of 20 this type and the substitution therefore of a vibrating reed and connections thereto to keep the clock movement in synchronism with the A. C. current.

A further object of my invention is the provision of a frequency reducer to step down the frequency of the current to a sub-multiple value and then by means of a vibrating member in step with said reduced current to bring a clock movement in 25 step therewith. The frequency reducing means 30 may be electrical, mechanical or a combination of both, as is most convenient for the particular conditions to be met.

The above and other objects of my invention will be described in the following specification 35 and set forth in the claims.

Before giving a detailed description of the mechanism of my invention, I will first give a short description of the principles on which it is based. In the preferred form of my invention, 40 I employ a continuously running clock movement, the power to run which may be obtained from the source of regulated current. Alternatively, the clock may be wound by hand or by any suitable battery actuated wind. The clock 45 escapement is of the recoil type, since as will be afterwards pointed out, I am not concerned that it keep exact time. The balance wheel of the clock, or the pendulum, as the case may be, is more or less governed as to its time of vibration by a spring or its equivalent. The other end of 50 this spring is arranged to be vibrated periodically by an element actuated in step with the current and preferably at some frequency which is a sub-multiple of the current frequency, for instance,

one-half or one-third. I have discovered that even if the frequency at which the end of the spring is vibrated is a multiple of the natural frequency of the balance and its spring, the balance will be forced into step.

To take a specific case: Assume that the balance of the clock makes three oscillations per second and that the current frequency is 60. Then there is a factor of 20 between the balance and the current. A factor of 5 may be taken care of between 10 the current and the member vibrated by said current and a factor of 4 between the vibrating member and the balance. That is, an electromagnet, excited by the 60 cycle current, vibrates a reed at a frequency of 12 and the reed vibrates 15 the end of the balance spring at a frequency of 12 (four times the frequency of the balance system) and thus keeps the balance, whose frequency is three, in step, both with the reed and the current. By means of this system of frequency reduction, 20 I do not need a synchronous motor and its associated system of gear reduction, and am free also from the concomitant lubrication troubles.

With the help of these preliminary remarks, 25 my invention may be best understood by reference to the accompanying drawing of which:—Fig. 1 is a diagrammatic drawing of a clock embodying my herein described invention and Fig. 2 is an alternative circuit which may be used therewith. In Fig. 1, for the sake of clearness, the balance 30 and escapement are shown on a larger scale than the remainder of the clock.

In Fig. 1, 10 and 11 are line conductors which supply regulated current. These are connected by wires 12 and 13 to a winding 14 on an electromagnet 15, having curved poles 16 and 17 which define an alternating magnetic field in which vibrates a reed 18, held by a block 19 in the framework. The reed 18 supports a block 20 in which is a timing screw 21 to adjust the frequency of 40 the reed. The reed 18 also supports an arm 22 to which is secured one end of a balance spring 23 whose other end is fastened to a balance staff 24. A balance 25 is on the staff 24 and is provided with four timing screws of which two, 26 45 and 27, are shown. The staff 24 is also provided with two arms 28 and 29 projecting therefrom and alternately engaged by the pins 30 in a crown wheel 31 mounted on a staff 32. The arms 28 and 29 with the pins 30 will be recognized as 50 forming the well-known verge escapement.

Power is supplied to the wheel 31 in the usual manner by a pinion 33 on the staff 32 engaging a wheel 34 on a staff 35 having a pinion 36 driven by a wheel 37 on a staff 38 which carries a pinion 55

39 driven by the center wheel 40 on a staff 41 revolving once an hour. The staff 41 carries a minute hand 43 and a cannon pinion 42 which drives an intermediate wheel 43 turning on a 5 stud 45. A pinion 44 on the wheel 43 turns a wheel (not shown) to which is attached the hour hand 41.

Power is supplied to the center wheel 40 by a gear 48 meshing therewith; said gear is on a shaft 10 49 to which is attached one end of a mainspring 56 mounted in a barrel 52, the inside of which is frictionally engaged by a spring clip 51 to which is fastened the outside end of the spring 56. Said spring is wound to a certain tension, after which 15 the clip 51 starts to slip in the barrel 52, thereby preventing further winding of the spring. The barrel 52 is provided with teeth 53 which are driven by a worm 54 on a shaft 55 which carries a wheel 56, driven by a worm 57 on a shaft 58 on 20 which is a conducting disc 59, driven by the alternating field of the electromagnet 60 with shaded poles 61. All of the above described motor mechanism is well known and does not require extended description. The magnet 60 is excited by a 25 winding 62 connected by wires 63 and 64 to the line wires 10 and 11.

From the preceding, the operation of my improved clock will be clear. The line current drives the disc 59 which, by the connecting gears, turns the barrel 52 and winds the spring 56 faster than the running of the clock will unwind the shaft 49, excess wind being taken care of by the slip of the clip 51. Driven by the clock train, the verge escapement vibrates the balance 25 at a rate approximately determined by the spring 23. The reed 18 is vibrated by the regulated current and on account of its connection with the end of the balance spring 23 holds the balance 25 in step. Thus the hands of the clock will revolve 40 at a rate determined by the frequency of the regulated current.

In the event the current is interrupted, the stored power of the spring 56 will keep the clock going until said spring is run down. When the current is again resumed, the reed 18 will pick up 45 its vibration and the balance will be held in step again, with the error of the clock that accumulated during a period of no current. However, the periods of no current in the ordinary commercial system are quite rare and of short duration so the time kept by my herein described clock will be practically that determined by the frequency 50 of the regulated current.

In Fig. 2, I have shown an electrical method of 55 reducing the frequency of the regulated current by means of a multivibrator circuit well-known in the radio art. This device, with an input of say 60 cycles, will give an output of some submultiple of 60, say 6 cycles per second. The submultiple 60 frequency is held rigorously with the main frequency. The circuits and description for the multivibrator may be found in Radio Engineering Principles, Lauer and Brown, second edition, page 208 et seq. McGraw-Hill Book Co. 1928; also 65 in Reception des Signaux Horaires page 68 et seq., published for the Bureau of Longitudes Paris by Gauthier-Villars et Cie., Quai des Grands-Augustine 55, in 1924. In the figure, a multivibrator 70 67 is connected to the line wires 10 and 11. Conductors 65 and 66 connect the multivibrators 67 with the winding 14 of the magnet 14. In the event of using the circuit shown in Fig. 2, the multivibrator may reduce the frequency 10 times to 75 a frequency of 6, the reed 18 may reduce 2 times

to a frequency of 3, which may be the frequency of the balance 25.

It will be obvious that the reduction factor may be distributed in any desired manner between the agencies of the multivibrator, the reed, and the balance. It is necessary only that their combined product be the frequency of the regulated current. This property gives a flexibility to meet varied requirements which my invention may have to meet.

The reed 18 has a large restoring force compared to the spring 23, so that the force of the latter may be swamped in the force of the former. It is also preferable that the reed 18 be polarized which may be done both by making it a permanent magnet or providing a permanent magnetic field to polarize it.

In the following claims, I have used the term "submultiple frequency" by which I mean a frequency which is that of the fundamental divided 20 by an integer other than one. For example, 12 is a submultiple of 60 since it equals 60 divided by 5.

I consider the use of a vibrating reed as a substitute for a synchronous motor in clocks of this kind of great advantage, it is self-starting and has 25 no lubrication troubles.

Many changes and modifications may be made in the precise structure herein shown without departing from the spirit of my invention since I claim:—

1. In an electric clock, the combination of a source of alternating current, an oscillating member, a spring connected to said member, a reed vibrating in step with said current, and a connection between said reed and said spring where- 35 by said oscillating member is kept in step with said current.

2. In an electric clock the combination of a source of alternating current, an oscillating member, a spring connected to said member, a reed 40 vibrating in step with said current at submultiple frequency and a connection between said reed and said spring whereby said oscillating member is kept in step with said current.

3. In an electric clock the combination of a 45 source of alternating current, and oscillating member, a recoil escapement to drive said oscillating member, a spring connected to said member a reed vibrating in step with said current at submultiple frequency and a connection between 50 said reed and said spring whereby said oscillating member is kept in step with said current.

4. In an electric clock, the combination of a source of alternating current, a reed vibrated by said current, at a certain frequency, a balance 55 having a frequency a submultiple of that of said reed and means whereby said reed forces said balance into step with said current.

5. In an electric clock the combination of a source of alternating current having a certain 60 frequency, an electromagnet connected to said current having an armature vibrating at a submultiple frequency, a balance having a submultiple frequency to that of said armature and connections between said armature and said balance 65 to hold said balance in step with said current.

6. In an electric clock the combination of a source of alternating current, a reed vibrated by said current at a submultiple frequency of said current, a balance having a submultiple fre- 70 quency to said reed and a spring having one end attached to said reed and the other end attached to said balance.
